UNITED STATES PATENT OFFICE

ELNATHAN SWEET, OF PORTLAND, OREGON.

DESIGN FOR A BACK FOR CARDS.

43,857.

Specification for Design.

Patented Apr. 15, 1913.

Application filed June 3, 1912. Serial No. 701,470. Term of patent 14 years.

To all whom it may concern:

Be it known that I, ELNATHAN SWEET, a citizen of the United States, residing in the city of Portland, county of Multnomah, and State of Oregon, have invented a new, original, and ornamental Design for Backs for Cards, of which the following is a specification, reference being had to the accompanying drawing, forming part thereof.

The figure is a plan view of the back of a card showing my new design, being a

graphic representation of the "coming" and "going" as related, respectively, to debit "Dr." and credit "Cr." in the science of bookkeeping.

I claim:

An ornamental design for a back for cards as shown and described.

ELNATHAN SWEET.
